UNITED STATES PATENT OFFICE.

LEO LAWRENCE MIVELAZ, OF MEMPHIS, TENNESSEE.

FINGERPRINT-SHEET HOLDER.

Application filed July 26, 1922. Serial No. 577,655.

To all whom it may concern:

Be it known that I, LEO L. MIVELAZ, a citizen of the United States, residing at Memphis, in the county of Shelby and 5 State of Tennessee, have invented new and useful Improvements in Fingerprint-Sheet Holders, of which the following is a specification.

This invention relates to a holder for 10 paper sheets, the general object of the invention being to provide a holder of slightly curve shape in cross section to hold sheets of paper upon which finger prints are to be made, so that the device can be used for 15 taking the prints of the fingers of corpses, cripples or of persons whose fingers are stiff or of those who try to prevent the prints being taken.

Another object of the invention is to provide 20 means whereby a number of sheets can be placed in the holder and used one at a time, the used sheet being removed from the top of the pile.

The invention also consists in certain 25 other features of construction and in the combination and arrangement of the several parts, to be hereinafter fully described, illustrated in the accompanying drawings and specifically pointed out in the appended 30 claim.

In describing my invention in detail, reference will be had to the accompanying drawings wherein like characters denote 35 like or corresponding parts throughout the several views, and in which:—

Figure 1 is a front view of the device.

Figure 2 is a sectional view on the line 2—2 of Figure 1.

Figure 3 is a sectional view on the line 40 3—3 of Figure 1.

Figure 4 is a view of the plate.

Figure 5 is a view of one of the sheets.

As shown in these views, the device comprises a handle 1 having an enlarged end 45 on which is secured a flanged frame 2, the whole forming a receptacle having its outer end open and also having an opening in its front through which the fingers may be placed against the sheets in the frame. A plate 3 is adapted to slide in the receptacle 50 through its open end and this plate is provided with a pin 4 over which the sheets of paper, shown at 5, are placed so that they will be secured to the plate. The plate

forms a support for a pile of sheets, each 55 sheet being provided with a hole to receive the pin, as shown at 6, and with a lip 7 which is separated from the body of the sheet by a perforated line 8. The frame, the enlarged end of the handle and the 60 plate are slightly curved as shown so that the sheets are also curved. Thus the top sheet can be rolled over a stiff finger to get the impression of the ridges thereon, so that this device will facilitate the securing of 65 prints which are ordinarily difficult to get. The rear of the device carries a set screw 9 for engaging the plate so as to force the same with the paper sheets thereon against the flanges of the frame and thus hold the 70 sheets in the device by pressure. The front end of the plate is provided with a nail receiving notch 10 so that the plate can be easily drawn from the receptacle. The lips provide means for drawing the sheets from 75 the device. After the sheets are removed the lips can be torn off the sheets and the sheets filed away in the usual manner, after being pasted on cards or the like.

This device permits the sheet of paper to 80 be rolled over the finger instead of the finger being rolled over the sheet, thus prints of the fingers of corpses, cripples and others whose fingers are stiff, can easily be taken.

It is thought from the foregoing description that the advantages and novel features 85 of my invention will be readily apparent.

I desire it to be understood that I may make changes in the construction and in the combination and arrangement of the several 90 parts, provided that such changes fall within the scope of the appended claim.

Having thus described my invention what I claim as new, and desire to secure by Letters Patent, is:—

A holder for finger print sheets comprising a handle part having a receptacle formed at one end thereof, one end and the front of the receptacle being open, a plate removably arranged in the receptacle, a pin 100 on the plate for holding the sheets thereon and a set screw at the rear of the handle part for engaging the plate to force the same with the sheets thereon against the front of the receptacle.

In testimony whereof I affix my signature.

LEO LAWRENCE MIVELAZ.
